UNITED STATES PATENT OFFICE.

ALBERT A. BECKETT, OF CHICAGO, ILLINOIS, ASSIGNOR OF ONE-HALF TO
JOHN KELLY, OF SAME PLACE.

FIRE-ESCAPE.

SPECIFICATION forming part of Letters Patent No. 280,311, dated December 18, 1883.

Application filed April 3, 1883. (No model.)

To all whom it may concern:

Be it known that I, ALBERT A. BECKETT, a citizen of the United States, residing at Chicago, in the county of Cook and State of Illinois, have invented certain new and useful Improvements in Fire-Escapes, of which the following is a specification, reference being had therein to the accompanying drawings.

My invention relates to certain new and useful improvements in fire-escapes.

The object of my improvement is to facilitate the escape of people from a burning building. I attain this object by means of the peculiar construction and arrangement of the various parts of my device, which will be more fully pointed out and described in the specification and claims, reference being had to the drawings accompanying this application and forming part of the same, in which—

Figure 1 is a perspective view of my invention, showing the truck in place with standards extended and netting spread. Fig. 2 is a detail view of the same, showing the position of pulleys and ropes. Fig. 3 is a detail view, showing the wedge.

Similar letters refer to similar parts throughout the drawings.

Referring to the drawings, letter A represents a truck; B and B', the sills, to which are pivoted the standards *a a* and *b b*. The bed strips or sills B and B' are formed of sufficient length and thickness for strength and utility, and are suitably mounted on a truck.

On the upper faces of sills B and B', a short distance from their ends, are secured metal strips *a²* and *b²*, each of said strips being provided centrally with projecting ears, having perforations for the reception of pivot-pins.

Near the rear ends of sills B and B' are secured projecting stakes or uprights *c*, formed with U-shaped ends, and braces *c'*, extending from the inner face of said stakes to the metal strips *b²*.

The rear ends of strips B and B' are formed with eyebolts or clips *c²*, into which are secured the ends of ropes *e*. The opposite ends of said ropes are secured to eyebolts or clips at the outer ends of standards *b*, the inner ends of said standards being shod with metal thimbles *b'*, and terminating between the projecting lips of the metal strips *b²* on the sills B and B'.

Said standards are provided with a cross-bar, *l*, by which they are held at a suitable distance apart. The ends of standards B and B', where they connect with the strips *b²*, are perforated to receive a pivot-bolt that passes through said projecting lips, and by which said standards are held in place on said sills. Standards *a a* are formed in a similar manner with metal thimbles *a'*, and connected by pivot-pins to metal strips *a²* by means of the projecting ears, as shown.

To the front ends of sills B and B' are pivoted loose pulleys *g²* and *g³*, and a short distance in rear of strips *a²*, on the under side of said sills, are pivoted loose pulleys *g* and *g'*. A short distance in rear of said pulleys *g* and *g'* are secured projecting stakes *d*, having U-shaped ends adapted to receive the standards *a* when tilted back. Said stakes are stiffened by means of braces *d²*, the upper ends of which are secured to said stakes *d*, and the lower ends of the same to the metal strips *a²*.

Pulleys *g⁴* and *g⁵* are pivoted between the cross-bar *m* and the front axle of the truck, near the center of the same, with sufficient space between the said pulleys to permit the rope *f* to pass loosely. One end of rope *f* is secured to the outer end of standard *a*, and passes down over the pulley *g³*, thence rearward around the pulley *g'*, thence forward between the pulleys *g⁴* and *g⁵*, to and through the clip-eye *h* on whiffletree *h*, thence rearward between the pulleys *g⁴* and *g⁵*, to and around the pulley *g*, thence forward over pulley *g²*, and up to the outer end of the opposite standard *a*, where its end is secured.

The outer ends of standards *a a* and *b b* are connected by means of a wire rope or cord, or they may be joined by means of rods of metal or wood. Depending and secured to said ropes or cords is a netting, formed of wire or other suitable material, *D*, and extending downward from said ropes or cords are ladders *k* and *k'*, the outer ends of said ladders being secured to said ropes, and the inner ends of the same secured to the sills B and B'.

For the purpose of securing the standards *a a* and *b b* and the netting *D* in any desired position for use, a wedge, *C*, is formed with concaved sides, and adapted to fit tightly between the pulleys *g²* and *g³*, and when forced be-

between the same to tightly grip the double rope *f*, thereby preventing any movement of the same, and holding the standards, netting, and ladders securely in place.

5 Before starting to a fire the standards are lowered by slackening up the rope *f* until they rest in the U-shaped ends of stakes *c c* and *d d*, when the whiffletrees *h* are secured to a hook under the seat *i*. The device is driven to the burning building, backed up to the building or near to the same. When the brake *j* is applied, the whiffletrees *h* are released and the team driven forward, or the team unhooked and the rope *f* pulled out by hand until the standards *a a* and *b b* are drawn by means of rope *f* into the position shown in Fig. 1. When the netting *D* is properly stretched and all the parts are in place, the wedge *C* is inserted by the attendant between the ropes *f* and the pulleys *g¹* and *g²*; when all the parts are securely held in place. From the open windows above any person can jump into or onto the netting *D* with impunity and safety without fear of injury, and then descend in safety by means of the ladders *k* and *k'* to the truck, and from thence to the sidewalk or street.

15 25 By this simple and effective means many people can be saved from burning buildings that would otherwise be lost.

Having thus described my invention, what I desire to secure by Letters Patent is—

1. In a fire-truck, the standards *a a* and *b b*, having cross-bars *l* and *l'*, said standards being pivoted to the frame of said truck, the outer ends of the said standards connected to a netting, with means for extending and holding the same in place, substantially as and for the purpose set forth.

2. In combination, the frame *A*, the standards *a a* and *b b*, pivoted, as described, the cross-bars *l* and *l'*, the ropes *e e*, and the netting *D*, with the rope *f*, pulleys *g g' g² g³ g⁴ g⁵*, and the wedge *C*, substantially as shown and specified.

3. In combination, the frame *A*, mounted on a truck, the standards *a a* and *b b*, the metal strips *a¹ a²* and *b¹ b²*, stakes *c c* and *d d*, ropes *e e*, netting *D*, and the ladders *k k'*, with rope *f*, whiffletrees *h*, pulleys *g g' g² g³ g⁴ g⁵*, the brake *j*, and the wedge *C*, substantially as shown and specified.

In testimony whereof I affix my signature in the presence of two witnesses.

ALBERT A. BECKETT.
